UNITED STATES PATENT OFFICE.

ROBERT FARIES, OF DECATUR, ILLINOIS.

DESIGN FOR A HOLDER FOR SHADES OF INCANDESCENT LAMPS.

SPECIFICATION forming part of Design No. 28,596, dated May 10, 1898.

Application filed December 22, 1897. Serial No. 663,102. Term of patent 7 years.

To all whom it may concern:

Be it known that I, ROBERT FARIES, of Decatur, in the county of Macon and State of Illinois, have invented a certain new and useful Design for a Shade-Holder for Incandescent Lamps, of which the following is a specification.

This design is exemplified in the drawings forming a part of this specification, in which—

10 Figure 1 is a plan, and Fig. 2 an elevation.

The distinguishing characteristics of the design are represented by a hollow cylinder surmounted by a set of strips converging toward a line extended through the axis of the cylinder and zigzagged near their apexes. The cylinder is shown at 1, the strips at 2, and the zigzag turns at 3 and 4. The bases of the strips are seated on and form a continuation of the upper edge of the cylinder as it ap-

pears in the drawings. They are tapered, 20 they converge somewhat in their general inclination, they zigzag outward and inward, as shown at 3, and outward again, as shown at 4, and their lengths and location of zigzag turns are uniformly the same. 25

The essential features of the design reside in the shape of the strips and their relation to the cylinder.

What I claim is—

The design for a holder for shades of incandescent lamps, substantially as herein shown and described. 30

In testimony whereof I sign my name in the presence of two subscribing witnesses.

ROBT. FARIES.
